UNITED STATES PATENT OFFICE.

CICERO HINE, OF CHICAGO, ILLINOIS, ASSIGNOR TO THE BRUNSWICK-BALKE-COLLENDER CO., OF CHICAGO, ILLINOIS, A CORPORATION OF DELAWARE.

DESIGN FOR A BILLIARD-TABLE.

41,864.

Specification for Design.

Patented Oct. 24, 1911.

Application filed June 9, 1911. Serial No. 632,249. Term of patent 14 years.

To all whom it may concern:

Be it known that I, CICERO HINE, a citizen of the United States, residing at Chicago, in the county of Cook and State of Illinois, have invented a new, original, and ornamental Design for Billiard-Tables, of which the following is a specification, reference being had to the accompanying drawing, forming a part thereof.

Figure 1 is a side elevation of a table

showing the design and Fig. 2 is an end view of a table embodying the present invention.

I claim:

The ornamental design for a billiard table, as shown.

CICERO HINE.
